UNITED STATES PATENT OFFICE.

GEORGE E. MARCH AND WARREN L. TENNY, OF MUSKEGON HEIGHTS, MICHIGAN.

DRINKING-FOUNTAIN.

992,436.

Specification of Letters Patent. Patented May 16, 1911.

Application filed May 5, 1910. Serial No. 559,470.

To all whom it may concern:

Be it known that we, GEORGE E. MARCH and WARREN L. TENNY, both citizens of the United States, residing at Muskegon Heights, county of Muskegon, State of Michigan, have made a certain new and useful Invention in Drinking-Fountains, of which the following is a specification.

The invention relates to drinking fountains, and particularly to that class of devices of this nature which are designed to be connected to spigots, fittings, or other connections of water supply pipes, and provided with a drinking cup.

15 The object of the invention is to provide a drinking fountain of the nature referred to which is simple and efficient, and capable of ready application for use.

A further object is to provide means in 20 a device of the nature referred to for equalizing the pressure and flow of water supplied to and through the drinking cup of the device.

A further object is to provide means for 25 efficiently draining the drinking cup and its fitting.

Other objects of the invention will appear more fully hereinafter.

The invention consists substantially in 30 the construction, combination, location and relative arrangement of parts, all as will be more fully hereinafter set forth, as shown in the accompanying drawing and finally pointed out in the appended claims.

35 In the drawing:—Figure 1 is a view in top plan of a drinking fountain constructed in accordance with the principles of our invention. Fig. 2 is a view in vertical, central, longitudinal section of the same, on the line 2, 2, Fig. 1, looking in the direction of the arrows. Fig. 3 is a detached detail view in perspective of a slotted and bored plug forming a tortuous passage for the water passing through the device. Fig. 4 is a 45 similar view of the cap nut for securing the cup in position.

The cups, glasses or other drinking utensils employed in schools, railway stations or other public places, as well as in homes, 50 restaurants, offices and the like, are frequently the means for transmitting disease germs through the indiscriminate use and re-use thereof without being properly cleansed.

55 It is among the special purposes of our invention to provide a drinking fountain

capable of being readily and easily attached to any ordinary water supply pipe, and wherein the drinking cup need not be touched when required for use, and is constantly kept fresh and clean, free from germs and efficiently drained.

In carrying out our invention we provide a short section of tube having at one end means for securing the same to a water supply pipe, and a stop cock or valve for opening and closing the same to the water supply, the other end of said tube having a drinking cup attached thereto in such relation that the water passing through the tube delivers upwardly into and through the cup centrally from the bottom thereof.

In the drawing, reference letter A designates the short tube, B the fitting at one end thereof for attaching the same to a 75 water supply pipe. In the form shown, the end of the tube is threaded and a correspondingly threaded socket in the fitting B, screws thereon. A plug valve or stop cock, the handle of which is shown at C, and 80 which may be of the usual, ordinary or any well known construction is associated with the fitting B. The other end of tube A is arranged to extend into a drinking cup D, centrally through the bottom thereof, the 85 cup D, being clamped or held in place in any suitable or convenient manner, as, for instance, by the screw nut E, and cap nut F, threaded upon the end of tube A, the bottom of the cup being clamped between these 90 nuts. In practice we prefer to so bend or shape the tube A, that when attached to a water supply pipe the end thereof which extends into the drinking cup is vertical 95 thereby supporting the drinking cup with its upper edge in substantially horizontal and level position. To accomplish this result in a simple manner the tube A may be bent in to the familiar curvature of a pipe stem, the drinking cup D corresponding to 100 the pipe bowl, although, instead of the tube A communicating with the interior of the drinking cup through an opening in the side thereof, as is customary with pipes, the tube delivers into the drinking cup centrally through the bottom thereof.

Usually the pressure in water supply pipes is subjected to more or less variation. In the use of a drinking fountain of the class to which our invention relates it is 110 desirable to equalize the pressure and flow of water into and through the drinking

cup. In order to accomplish this result, in accordance with the principles of our invention, we provide means to cause the current of water to react upon itself as it flows 5 through the tube A, whereby a substantially uniform flow of the water into and through the drinking cup is secured. This result may be accomplished in various ways within the broadest scope of our invention as defined in the claims. A simple arrangement is shown wherein a tortuous passage for the water through the tube is provided.

In the particular embodiment which we have shown in the drawings to illustrate our 15 invention, we insert a plug G, at some convenient point in the tube A, or fitting B, as, for instance, in the end of tube A, to which the fitting B, is attached. This plug is provided with a small hole H, drilled longitudinally 20 through a portion of the length thereof, and terminating in a laterally disposed slit or opening J, cut into the side of the plug near one end thereof, thereby presenting a flat wall transversely the length of the 25 longitudinal hole or passage H, the end of the plug in which the slit or cut J is made being tapered, as shown. With this arrangement it will be seen that the current of water flowing through the fitting B, when 30 the stop cock therein is opened, will pass through the bore H, of plug G, and, encountering the flat transverse surface of the solid end wall of the lateral slit or cut J, will react upon itself and flow out laterally 35 through said slit or cut and around the tapered end of the plug into the enlarged bore of the tube A, and through the bottom thereof. The tortuous passage thus provided as a means for causing the current of water 40 to react upon itself, presents a constricted passage which terminates against a transverse flat solid wall with an abrupt lateral opening from the constricted passage into the enlarged area of the bore of tube A, 45 thereby efficiently equalizing the pressure of the water and securing a uniform current flow into and through the drinking cup. Thus the cup is held in an upright position with its upper edge level. The water entering 50 the cup from a point centrally of the bottom thereof rises evenly and gently in a column through the body of water in the cup, instead of spouting up in a jet, forming an evenly rounded hill, so to speak, in 55 the center of the water in the cup, finally overflowing the rim of the cup all the way around, keeping such rim clean.

If desired, and in order to drain the device when not in use, we provide openings 60 K, through the end of the tube to which the drinking cup is attached, and which afford passages from the bottom of the cup back into the tube. We also provide an opening, indicated at M, in the lowest part of the 65 tube A. By these means the device is effi-

ciently drained when not in use, thereby avoiding the accumulation of dust or germs in the water which would otherwise remain standing in the cup and tube when the valve cock is shut off. Consequently fresh clean 70 water from the supply pipe is assured at all times when the valve is open for the use of the device.

Having now set forth the object and nature of our invention, and a construction embodying the principles thereof, what we claim as new and useful and of our own invention, and desire to secure by Letters Patent is,

1. In a drinking fountain, a drinking cup, 80 a tube delivering into the same, a plug tapered at one end and fitting into the end of the tube, said plug having a transverse slit in the tapered end thereof, and a longitudinal bore delivering to said slit, and means 85 for connecting said tube to a water supply pipe.

2. In a drinking fountain, a cup, a tube for connection with a source of water supply and delivering freely into the cup 90 through the bottom thereof, a plug arranged in said tube and having an exteriorly tapered end and a longitudinal bore, and having a flat wall interposed therein transverse to the bore thereof against which the water 95 flowing through said bore impinges, and a lateral passage around said flat wall.

3. In a drinking fountain, a cup, a tube for connection with a source of water supply and delivering freely into the cup 100 through the bottom thereof, a plug fitting into said tube, said plug having an exteriorly tapered end and a longitudinal bore and a lateral passage, the wall of said passage presenting a flat surface transverse to 105 said bore and against which the water flowing through said bore impinges, whereby the flow of water is directed through the lateral passage and its pressure is equalized.

4. In a drinking fountain, a cup arranged 110 in a vertical position, a tube for connection at one end with a source of water supply and having its other end extending vertically into the cup through the bottom thereof, and delivering freely into the bottom of the cup, the end of the tube which extends into the cup having lateral openings on a level with the inner surface of the lowest part of the bottom of the cup, said tube having a drainage opening in its lowest 115 part.

5. In a drinking fountain, a cup arranged in a vertical position, a tube for connection at one end with a source of water supply and having its other end extending vertically 125 into the cup through the bottom thereof and delivering freely into the bottom of the cup, the end of the tube which extends into the cup having lateral openings on a level with the inner surface of the lowest part of the 130

bottom of the cup, the tube having a vertically curved portion in the length thereof provided with a drainage opening in its lowest part.

- 5 6. In a drinking fountain, a cup arranged in a vertical position, a tube for connection at one end with a source of water supply and having its other end extending vertically into the cup through the bottom thereof and 10 delivering freely into the bottom of the cup, the end of the tube which extends into the cup having lateral drainage openings on a level with the inner surface of the lowest

part of the bottom of the cup, said tube having a drainage opening in its lowest part and 15 means arranged in the tube to equalize the pressure of the flow of water therein.

In testimony whereof we have hereunto set our hands in the presence of the subscribing witnesses, on this 26th day of April 20 A. D., 1910.

GEORGE E. MARCH.
WARREN L. TENNY.
